FIREPLACE SCREEN SUPPORTING FIXTURE

Filed March 7, 1939

FIG. 1

FIG. 5

FIG. 2

FIG. 3

FIG. 4

A technical drawing of a gear assembly. It features a central gear with a diameter of 20. A larger gear above it has a diameter of 11 and a thickness of 8. A smaller gear below it has a diameter of 16 and a thickness of 8. A pinion gear to the left has a diameter of 5 and a thickness of 19. A horizontal dimension line at the bottom is labeled 8.

FIREPLACE SCREEN SUPPORTING FIXTURE

John B. Turner, Norwich, N. Y.

Application March 7, 1939, Serial No. 260,302

9 Claims. (Cl. 156—22)

In conjunction with the so-called flexible type of fireplace screens, it has, in the past, been customary either to support the screens within the fireplace or to provide brackets which are secured to the front or face of the fireplace for supporting across the front of the fireplace a rod from which the fireplace screens are suspended. When the screen supporting devices are so mounted as to support the screens within a fireplace, the horizontally extending rod upon which the screens are mounted must be of a length closely approximating the width of the fireplace opening and, hence, each rod must be provided in the correct length to meet the requirements of the particular fireplace with which it is to be employed. Furthermore, when mounting fireplace screens in the foregoing manner, the screens must, for each installation, be so fabricated in size as properly to hang within the fireplace opening with the lower edge in close proximity to the hearth. Since fireplaces do not usually conform to any particular or standard dimensions, either in height or width of fireplace opening, it follows that in order to mount fireplace screens within the fireplace, as above pointed out, both the screens and the supporting rods therefor should be especially fabricated in order properly to meet the requirements of each and every installation. Manufacturers, therefore, cannot fabricate and supply to dealers and the trade fireplace screens and supporting rods therefor in predetermined sizes or a series of standard sizes.

The other type of fixture for supporting fireplace screens, above mentioned, are designed to be secured to the face of a fireplace and to uphold a rod in substantially horizontally extending position across the front of the fireplace upon which the fireplace screens are mounted. A serious objection, however, to supporting the screens in this manner resides in the fact that the face of the fireplace must be drilled to permit the fixtures to be secured thereto.

The primary object of my present invention, therefore, resides in the provision of a fireplace screen supporting fixture which is adapted to be secured to an inner wall of a fireplace and which is so adjustably constructed and arranged that it may be applied to fireplaces of different heights and widths and will support a fireplace screen in proper and correct relation to the fireplace opening and hearth. In other words and more particularly, the fixture of my invention is so designed that elements thereof which, for example, may be secured to inner, side walls of a fireplace

5 for supporting a rod in substantially horizontally extending position across the front of the fireplace may be relatively adjusted whereby properly to space said elements for application to fireplace openings of different widths. At the same time, the fixture may also be adjusted so as to support a fireplace screen with the lower edge thereof in correct relation to the hearth whereby fireplace screens of given or standard heights 10 may be adjusted to fireplace openings of different heights and properly suspended in front thereof.

Still more particularly, my invention has for an object the provision of a fireplace screen supporting fixture comprising a rod adapted to extend substantially horizontally across the front of a fireplace, an element which is adapted to be secured to an inner wall of the fireplace and an arm connected between said rod and element, 15 said arm being so connected and arranged that said rod and element may be relatively adjusted to meet the size requirements of fireplace openings to which said fixture may be applied.

With these and other objects in view, my invention includes the novel elements and the combinations and arrangements thereof described below and illustrated in the accompanying drawing in which—

Fig. 1 is a fragmentary plan view of one form 20 of my invention;

Fig. 2 is a fragmentary elevation view thereof; 25 Fig. 3 is a fragmentary, sectional, elevation view thereof taken in about the plane 3—3 of Fig. 2;

Fig. 4 is an elevation, detail view of one element of the fixture of Fig. 1;

Fig. 5 is a fragmentary, elevation view illustrating the attachment of my fixture to a fireplace and the manner in which it may be adjusted. 30

Fig. 6 is a perspective view of a fireplace showing my invention applied thereto;

Fig. 7 is a fragmentary, elevation view of a modified form of fixture;

Fig. 8 is a fragmentary, sectional elevation view 35 thereof taken in about the plane 8—8 of Fig. 7; and

Fig. 9 is a fragmentary plan view of one of the elements of Fig. 7.

Since my invention contemplates the provision 40 of two, adjustable supporting elements for a rod adapted to extend horizontally across a fireplace and upon which the fireplace screens are supported, which elements are adapted to be secured to an inner wall of a fireplace and are connected respectively to said rod and adjacent opposite

ends thereof, I have illustrated in detail but one end of said rod and its associated supporting element, it being understood that the other supporting element is of like construction and adjustable in like manner.

Referring first to Figs. 1 to 3, 1 is a rod, illustrated as tubular (see Fig. 3), upon which the fireplace screens are adapted to be supported. The adjustable supporting elements which are associated with opposite ends of said rod comprise a curved arm 2 and an element 3 which is adapted to be secured to an inner wall of a fireplace. The arms are preferably of like shape but extend in opposite directions when supported to overlie the face of a fireplace as shown in Fig. 6. Arm 2 is connected adjacent one end thereof to the rod 1 and adjacent the other end thereof to the overbent portion 4 of the element 3. The main body of element 3 extends generally at right angles to the rod 1 and is adapted to be secured to the inner side wall 5 of the fireplace opening 6, as illustrated in Fig. 6. Openings 3' are provided in element 3 through which anchoring bolts may be passed to secure it to the fireplace wall. With this arrangement, of course, when the element 3 is secured to an inner, side wall of a fireplace, the overbent portion 4 which extends substantially at right angles to the main body of element 3 will overlie the face of the fireplace whereby to permit the arm 2 which is adjustably and pivotally connected thereto by means of the bolt 7 to be pivoted in a generally vertical plane. The overbent portion 4 is preferably drilled and tapped to receive the bolt 7 so that when the arm 2 is suitably adjusted relative thereto, bolt 7 may be tightened to hold the elements in relatively adjusted positions. To increase the friction between the arm 2 and overbent portion 4, the portion 4 may be roughened or knurled as indicated at 8 in Fig. 4 and, likewise, the end of arm 2 which frictionally engages the overbent portion 4 may also be roughened whereby to aid in firmly holding the elements in relatively adjusted positions.

For appearance, I prefer to employ a tubular rod with a slot 11 extending lengthwise thereof. The arm 2 may be slidably connected thereto by means of the bolt 9 which passes through the slot and nut 10 which is adapted to be received within the tubular rod 1 as illustrated in Fig. 2. By slidably connecting the arm 2 to the rod 1, an adjustment may be made whereby the fireplace screen will be properly supported relative to the hearth while the adjustable, pivotal connection between arm 2 and element 3 permits the elements 3 of the fixture to be relatively spaced to conform to the width of the fireplace opening when, for example, they are to be attached to the inner, side walls of the fireplace.

As illustrated in Fig. 6, the elements 3 of my fixture are adapted to be secured to opposite and inner side walls 5 of the fireplace opening 6 with the overbent portions 4 thereof overlying the front or face 11 of the fireplace. The arms 2, adjustably and pivotally connected to the portions 4 may extend upwardly and support the rod 1 in a substantially horizontally extending position across the fireplace. Upon the rod 1 are supported fireplace screens 12, only one of which is illustrated. In the embodiment illustrated, rings 13 serve to support the screen 12 on the rod 1 whereby the screen may be pulled as a curtain across the fireplace opening or moved to one side thereof.

In installing my fixture, it will be seen that due to the adjustable connections between the elements 3, arms 2 and the rod 1, the spacing between the two elements 3 may be varied both by pivoting the arms 2 relative to rod 1 and by sliding the arms 2 relative to the rod. Hence, my supporting fixture may, within limits, be so adjusted that the elements 3 thereof may be secured to opposite and inner side walls of fireplace openings of different widths. Furthermore, with the elements 3 in correctly spaced relation, arms 2 may then be pivoted relative thereto and slid relative to rod 1 to adjust the elevation of the rod relative to the hearth whereby the fireplace screens will be supported in proper relation to the opening and hearth.

Fig. 5 illustrates the manner in which the elevation of rod 1 above the hearth may be varied. The arm 2 is shown in dotted lines at 2' as pivoted in a clockwise direction relative to its supporting element 3 and adjusted relative to the rod 1 thereby supporting the rod at a higher elevation as indicated in dotted lines at 1'. Obviously, the supporting fixture which is mounted on the opposite side of the fireplace is likewise adjusted in order to support rod 1 substantially in a horizontal position.

From the foregoing, it is believed evident that, within limits, my supporting fixture may be adjusted to support a rod across fireplace openings of different widths and, at the same time, it may also be adjusted to support said rod at substantially the correct elevation above the hearth to meet the height requirements of a given fireplace screen. Hence, I have provided a fixture which may be secured within a fireplace opening but which is so constructed and arranged that fireplace screens need not be especially fabricated in height for each individual installation nor is it necessary to provide supporting rods for said screens in lengths conforming to the width of the fireplace opening. With my invention, rods may be provided in a limited number of different, standard lengths whereby the requirements of all ordinary fireplaces may be met. The rod most closely approximating the correct length may, of course, be chosen for any particular installation. Likewise, the fireplace screens may be fabricated in standard heights and, it will be evident, that by using the fixture of my invention a considerable saving in the cost of manufacturing both fireplace screens and supporting elements therefor will be experienced while the supply thereof to the trade may be more satisfactorily carried out.

The modified form of my invention illustrated in Figs. 7 to 9, is generally similar to that hereinbefore described but embodies a modified arm for connection to a tubular rod 14 which is slotted 55 along the bottom thereof, as indicated at 141, to receive a roller type supporting element for the fireplace screens. The tubular rod 14 is adjustably and slidably connected to the arcuate, overbent portion 15 of arm 16 and arm 16, like arm 2, is pivotally and adjustably connected to the element 17 corresponding to element 3. Element 17 may be generally L-shaped like element 3 and the main body thereof may be substantially straight whereas the end of element 3 remote from the overbent portion 4 thereof is shown as bent at a slight angle so that the element may conform to the slope of the inner, side walls of the ordinary fireplace. The arcuate portion 15 is provided with a slot, as indicated at 18, to

permit the shank of a bolt 19 to pass therethrough and be threaded into a nut 20 which is disposed within the tubular rod 14, as illustrated in Fig. 8.

Adjustment of arm 16 relative to rod 14 and element 11 may be accomplished in the same manner as that of arm 2 relative to rod 11 and element 3, the arcuate, overbent portion 15 of arm 16 affording proper engagement between the rod and arm when the arm and rod are positioned at various angles to each other.

While I have described my invention in its preferred embodiment, it is to be understood that the words which I have used are words of description and not of limitation. Hence, changes within the purview of the appended claims may be made without departing from the true scope and spirit of my invention in its broader aspects.

What I claim is:

1. In a fireplace screen supporting fixture, a rod adapted to extend horizontally across the front of a fireplace and to support a fireplace screen thereon, a generally L-shaped element adapted to be secured to an inner wall of said fireplace with a portion thereof overlying the face of said fireplace, an arm pivotally connected adjacent one end thereof to said L-shaped element and slidably connected adjacent its other end to said rod and means for securing said arm and rod against relative movement.

2. In a fireplace screen supporting fixture, a rod adapted to extend horizontally across the front of a fireplace and to support a fireplace screen thereon, a generally L-shaped element adapted to be secured to an inner wall of said fireplace with a portion thereof overlying the face of said fireplace, an arm pivotally connected adjacent one end thereof to said L-shaped element and slidably connected adjacent its other end to said rod, means for securing said arm and rod against relative movement and means for securing said arm and element against relative pivotal movement.

3. In a fireplace screen supporting fixture, a rod adapted to extend horizontally across the front of a fireplace and to support a fireplace screen thereon, a support for said rod comprising an element having an overbent portion, said element being adapted to be fastened to an inner wall of said fireplace with its overbent portion overlying the face of said fireplace, and means connected to said rod and to the overbent portion of said element for adjustably supporting said rod.

4. In a fireplace screen supporting fixture, a rod adapted to extend horizontally across the front of a fireplace and to support a fireplace screen thereon, a support for said rod comprising an element having an overbent portion, said element being adapted to be fastened to an inner wall of said fireplace with its overbent portion overlying the face of said fireplace, an arm attached to said rod and means for adjustably connecting said arm to the overbent portion of said element.

5. In a fireplace screen supporting fixture, a rod adapted to extend horizontally across the front of a fireplace and to support a fireplace screen thereon and a support for said rod comprising an element provided with means adapting it to be bolted to a wall of said fireplace, an arm pivotally mounted on said element; said element pivotally supporting said arm in a generally ver-

tical plane substantially parallel with the face of said fireplace when said element is secured to a wall of said fireplace and means for slidably connecting said arm to said rod; whereby the elevation at which said rod is supported may be varied.

6. In a fireplace screen supporting fixture, a rod adapted to extend horizontally across the front of a fireplace and to support a fireplace screen thereon and a support for said rod comprising an element provided with means adapting it to be bolted to an inner wall of said fireplace, an arm pivotally mounted on said element; said element pivotally supporting said arm in front of said fireplace and in a generally vertical plane substantially parallel with the face of said fireplace when said element is secured within said fireplace and means for slidably connecting said arm to said rod; whereby the elevation at which said rod is supported may be varied.

7. In a fireplace screen supporting fixture, a rod adapted to extend horizontally across the front of a fireplace and to support a fireplace screen thereon and a support for said rod comprising an element provided with means adapting it to be bolted to a wall of said fireplace, and means for adjustably supporting said rod on said element, said last mentioned means adjustably supporting said rod in a generally vertical plane substantially parallel with the face of said fireplace when said element is secured to a wall of said fireplace whereby the elevation at which said rod is supported may be varied.

8. In a fireplace screen supporting fixture, a rod adapted to extend horizontally across the front of a fireplace and to support a fireplace screen thereon and a support for said rod comprising an element provided with means adapting it to be bolted to a wall of said fireplace, and means pivotally connected at spaced points thereon to said rod and element for adjustably supporting said rod on said element, said last mentioned means also providing relative movement of said rod and element in a direction substantially parallel with said rod, and said last mentioned means adjustably supporting said rod in a generally vertical plane substantially parallel with the face of said fireplace when said element is secured to a wall of said fireplace whereby the elevation at which said rod is supported may be varied.

9. In a fireplace screen supporting fixture, a rod adapted to extend horizontally across the front of a fireplace and to support a fireplace screen thereon and a support for said rod comprising a pair of elements provided with means adapting them to be bolted to opposite walls of said fireplace, and means for adjustably connecting said rod adjacent opposite ends thereof to said elements and for adjustably supporting said rod thereon, said last mentioned means and rod adjustably connecting said elements for movement relative to each other in the general direction of the length of said rod and said last mentioned means adjustably supporting said rod in a generally vertical plane substantially parallel with the face of said fireplace when said elements are secured to the walls of said fireplace; whereby said fixture may be applied to fireplaces of different widths and the elevation at which said rod is supported may be varied.
